UNITED STATES PATENT OFFICE.

LA VERNE W. NOYES, OF CHICAGO, ILLINOIS, ASSIGNOR TO AERMOTOR COMPANY, OF CHICAGO, ILLINOIS, A CORPORATION OF ILLINOIS.

ENGINE.

1,086,845.

Specification of Letters Patent.

Patented Feb. 10, 1914.

Application filed February 3, 1911. Serial No. 606,349.

To all whom it may concern:

Be it known that I, LA VERNE W. NOYES, a citizen of the United States, residing at Chicago, in the county of Cook and State 5 of Illinois, have invented a certain new and useful Improvement in Engines, of which the following is a full, clear, concise, and exact description, reference being had to the accompanying drawings, forming a 10 part of this specification.

My invention relates to engines that include fly wheels in their formation and has for its object the provision of an improved engine base for supporting the fly wheel or 15 fly wheels of an engine clear of the level upon which the engine stands.

The preferred form of the invention, to which I do not wish to be limited, is shown in the accompanying drawings in which—

20 Figure 1 is a side elevation of an engine equipped in accordance with my invention; Fig. 2 is an end view thereof; and Fig. 3 is a sectional view on line *a—a* in Fig. 1.

Like parts are indicated by similar characters of reference throughout the different figures.

25 The invention specifically relates to reciprocating horizontal engines and is of special utility in connection with internal combustion engines, one form of which is illustrated in the drawings. Engines of this type are so well known that a description thereof in detail will not be necessary, it sufficing to mention those parts that are in 30 immediate association with the improved engine base and the relationship of the base to the fly wheel element of the engine.

35 The cylinder 1 is in this instance shown as being surrounded by a cooling jacket 2 which is in fixed and rigid relation with the cylinder, both cylinder and jacket being of cast metal and suitably united in a manner well known by those familiar with the art. The crank shaft 3 is journaled in suitable 40 bearings that are carried by an extension of the jacket 2, this crank shaft having propelling torque exerted thereupon and in turn governing the agencies by which such torque is produced, all as is well understood. The cast jacket 2 is provided with two pairs 45 of horizontally upsetting feet 4, 5 that are cast integrally therewith in close proximity to the cylinder. These feet are rested upon the upper longitudinal edges of the boards 50 6 that preferably slope so as to converge up-

wardly, these boards being of such a height as sufficiently to elevate the engine to a position in which the fly wheels 7, that are carried upon the crank shaft 3, are clear of the level upon which the bottom longitudinal edges of the boards rest, the horizontal engine overlying the space between the boards. The major portions of the stems of elongated bolts 8 rest against the inner and opposed faces of the boards 6 and are secured to the boards by means of bolts 9, these bolts having inner heads 10 that engage marginal portions of openings passed through the shanks of bolts 8 through which openings the threaded shanks of the bolts 9 are passed. The nuts 11 serve when tightened to cause the bolt heads 10 to clamp the bolts 8 very rigidly against the inner opposed side faces of the boards 6, whereby weakening bolt holes need not be formed in the boards. 75 The upper ends of the bolts 8, which are thus very firmly held in engagement with the boards 6, are preferably slightly deflected so as to extend in purely vertical directions and thereby be readily adapted for passage 80 through vertical openings provided in the horizontal upsetting feet 4 and 5, the upper ends of these bolts being threaded to receive nuts 12 that enable the feet to be clamped into very firm engagement with the top 85 longitudinal edges of the base boards 6. One pair of upsetting feet, say the feet 4, is provided with downwardly projecting feathers 13 that are received within transverse grooves 14 provided in the tops of the 90 base boards, to insure against creepage that might otherwise occur to a slight extent between the base boards and the balance of the engine structure, as for example in case of the lack of a snug fit between the feet 4 and 5 and the notches in the upper edges 95 of the base boards that receive these feet. Further to insure the rigid relation between the jacket 2 and the supporting base boards of the engine I employ bracing elements 15 100 extending across the space between the base boards from the upper parts of the base boards to their lower parts, these bracing elements being desirably integrally formed with the heads 10 of the bolts 9 as indicated. 105 Thus there are two pairs of bolts 8, the members of each pair being located substantially in the same plane that is at right angles to the planes of the base boards, the two pairs of bolts 8 being separated longitudinally 110

of the base boards, the bolts 8 of each pair being anchored in position by means of bolts 9 whose heads 10 engage the bolts 8 and whose nuts 11 upon the outsides of the base boards firmly clamp the heads 10 against the bolts 8, the head 10 of each upper bolt 9 being rigidly connected with the head 10 of the lower and opposite bolt 9 by a strut 15 which acts as a tension and compression member for the purpose of holding the base boards in rigid relation. Each element 15 thus forms, with the bolts 9 united therewith, a single bolt structure that includes a shank comprising the strut 15 and the deflected shank portions 9, the elements 10 then being in the nature of enlargements to perform the function for which they are provided, and while I prefer single bolt structure comprising the elements 9, 10, 11 and 15 that are capable of performing their functions individually and collectively I do not wish to be limited in all embodiments of my invention to such a structural characteristic, nor do I wish to be limited to other details of construction specifically illustrated since changes may be made without departing from the spirit of the invention.

As is well known, it is desirable to increase the diameters of engine fly wheels as far as is practicable within limitations imposed by surrounding conditions, in order to decrease the weight of the fly wheels but such an increase in the fly wheel diameter is accomplished by a corresponding elevation 35 of the fly wheel shaft thereby necessitating a correspondingly higher engine base to afford the necessary clearance between the fly wheel peripheries and the level upon which the engine rests. If this base were made of 40 cast iron, as hitherto, its weight would be increased to such an extent as to limit the extent to which the diameters of the fly wheels might otherwise be enlarged. The engine base of my invention is therefore of great 45 utility since wooden boards and a comparatively light truss structure intervening between the same would replace cast iron bases so that the factor furnished by the weight of the engine bases in limiting the 50 extent to which the fly wheels may be increased in diameter is removed.

Where the invention is embodied in a hydro-carbon engine, the engine base of my invention affords an excellent housing or support for the fuel oil receptacle 16 which 55 desirably has its sides sloping in conformity with the slopes of the inner opposed faces of the engine base board 6. The fuel oil can or receptacle 16 is located in position after

the engine base has been assembled with the balance of the engine, this can being pressed upwardly so as to be rigidly engaged between the base boards, whereafter cleats 17 are nailed upon the base boards beneath the fuel can to hold this can firmly in its 65 position. The cleats 17 are provided with upward extensions 18 at their ends to avoid possible longitudinal movement of the can 16 with respect to the engine base boards 6.

Having thus described my invention, I claim as new and desire to secure by Letters Patent the following:—

1. A reciprocating engine structure including a cylinder and fly wheel; feet located in close proximity to and in rigid relation 75 with the cylinder; engine supporting base boards placed on edge and upon the upper edges of which said feet rest; bolts clamped at their upper ends into engagement with the aforesaid feet, these bolts having elongated stems that rest against the base boards and having openings therein to enable the same to be clamped to the base boards; upper and lower bolts 9 having their shanks passing through the openings of each of the 85 aforesaid bolts and serving to clamp the aforesaid bolts into engagement with the base boards; and struts 15 uniting the upper bolts 9 of each of the base boards with the lower bolts 9 of the companion base board. 90

2. A reciprocating engine structure including a cylinder and fly wheel; feet located in close proximity to and in rigid relation with the cylinder; engine supporting base boards placed on edge and upon the 95 upper edges of which said feet rest; bolts clamped at their upper ends into engagement with the aforesaid feet, clamping devices serving to clamp said bolts to side faces of the base boards; and bracing mechanism intervening between the base boards. 100

3. A reciprocating engine structure including a cylinder and fly wheel; feet located in close proximity to and in rigid relation with the cylinder; engine supporting 105 base boards placed on edge and upon the upper edges of which said feet rest; bolts clamped into engagement with the aforesaid feet; and clamping devices serving to clamp said bolts to side faces of the base 110 boards.

In witness whereof, I hereunto subscribe my name this twenty third day of January A. D., 1911.

LA VERNE W. NOYES.
